UNITED STATES PATENT OFFICE.

SAMUEL M. PETTENGILL, OF BROOKLYN, NEW YORK.

ENDLESS-CABLE RAILWAY.

SPECIFICATION forming part of Letters Patent No. 230,808, dated August 3, 1880.

Application filed January 23, 1880.

To all whom it may concern:

Be it known that I, SAMUEL M. PETTENGILL, of Brooklyn, in the county of Kings and State of New York, have invented a new and 5 useful Improvement in Endless-Cable Railways, of which the following is a specification.

My improvements relate to railways provided with a moving endless cable, rope, or chain for propulsion of the cars; and the object of my invention is to furnish the cars with 10 means for seizing and firmly holding to the rope or cable without shock.

The invention is applicable to elevated, surface, and other railways, bridges, mines, or else- 15 where; and it consists in a clutch of peculiar construction operated by a lever, having combined with it a device for raising the traction-rope into the clutch, operated by the same lever. The devices are also fitted so that they will 20 safely pass the sheaves supporting the cables.

The construction and operation will be more particularly described with reference to the accompanying drawings, wherein—

Figure 1 is a vertical longitudinal section of 25 a car fitted with my invention and shown in connection with a track. Fig. 2 is an inverted plan view of the car. Fig. 3 is a vertical longitudinal section of the car in the reverse position of Fig. 1. Fig. 4 is a cross-section on 30 line *y y* of Fig. 2.

Similar letters of reference indicate corresponding parts.

The endless rope or chain *a* is fitted to run over sheaves *b*, which will be placed at suitable distances apart, and the rope driven in any usual or desired manner.

The clutching mechanism is fitted beneath each car *A*, about midway between the trucks, or wherever it can be placed most conveniently, 40 and is constructed and arranged as follows: *c c* are tubular guides, of any suitable lengths, sustained side by side and parallel to each other by the pillars *d*, that are bolted to the car-frame. The inner side of each guide *c* is slotted to receive the flange *e* of the slide *C*, that is fitted between the guides *c*, so that the slide is thereby sustained and may move in the guides lengthwise of the car. Within the guides *c* springs *f* are fitted at opposite sides 45 of the flanges *e*, such springs tending to retain the slide in a midway position.

The slide *C* is preferably made in the form shown in Fig. 4—that is, with a recessed under side—and is fitted in such recess with a clutch-lever, *g*, pivoted to swing in a horizontal direction and formed with a roughened end that is eccentric to the pivot, so that the rope may be clamped between such surface and one side of the recess, and the strain will act to tighten the clutch. In an aperture of slide *C* 55 a lever, *h*, is hung to swing in a vertical plane, one end of which lever is connected to clutch *g*, while the other end passes up through the bottom of the car, so as to be operated conveniently within the car.

To the bottom of the car, at the rear of slide *C*, a rod, *i*, is fitted in a fixed tubular guide, *k*, so as to be capable of vertical movement, and is supported at its upper end by a nut, *l*, that rests on guide *k*, whereby the rod *i* 60 may be adjusted vertically.

The rod *i* is forced downward by a spiral spring contained in the guide *k*, and is fitted at its lower end with two parallel spring-arms, *m*, that may be opened transversely of the 65 car, and are fitted at their inner sides with lugs or pins *m'*, which are normally in contact and serve to sustain the rope *a* and retain it in line with the clutch.

In suitable bearings on the upper side of slide *C* is fitted a cross-shaft, *n*, on one end of which is fixed a forked arm, *o*, that passes at opposite sides of rod *i* and engages with pins *i'* on the rod. The other end of shaft *n* is fitted with an arm or disk, *p*, having a pin, *p'*, 75 that extends in front of lever *h*. The lever *h* is fitted for sidewise movement on its fulcrum, so that as it is moved forward to clutch the rope it may be engaged with the pin *p'* to move the rod *i* upward, as hereinafter de- 80 90 scribed.

Beneath the car, in front of the slide *C*, is hung an arm, *q*, having its lower end bent horizontally to pass above the rope *a*, and connected by a link, *r*, with lever *h*, so that as 95 the arm *q* is moved the lever *h* moves with it to relieve the rope from the clutch.

The operation is as follows: When the rope is to be clutched for moving the car the lever *h* is moved forward in engagement with the pin *p'*, thereby simultaneously moving the clutch-lever *g*, raising the rod *i* and springs *m*, and 100

moving the arm *q* forward. The forked arm *o* being long, the rod *i* is rapidly raised, and the rope raised into the clutch before it closes. The further movement of lever *h* clamps the 5 rope, when the pin *p'* will be disengaged by a slight side movement of lever *h*, and rod *i* will fall downward.

The clutch is automatically released at each sheave *b* by contact of the arm *q* with the sheave, 10 which forces the said arm and lever *h* backward, and at the same time presses rope *a* downward from the clutch.

The strain in starting the car by clutching the rope, as described, is relieved by the forward movement of the slide *C* in guides *c*, 15 which is taken by the springs and the slide gradually stopped until the inertia of the car is overcome. The clutching may be done gradually until the full speed is obtained and the 20 mechanism thereby relieved of shock.

The strain of the rope on the clutch tends to bind the rope more firmly, and to relieve the rope it is only necessary to pull the lever back, and the rope will drop upon the pins *m'* 25 of springs *m*.

To permit the car to pass the sheaves *b* without the springs *m* interfering therewith, the springs *m* are fitted at the lower end with flanges *s*, that extend forward and flare outward, so that when they reach the sheave the 30 flanges *s* will pass at opposite sides thereof, open the springs *m*, and allow the pins *m'* to leave the rope and pass at each side of the sheave without touching. They also pass the 35 sheave of the next section of rope in the same manner, and then close under the rope.

This mechanism is simple and durable, and may be applied to cars of usual construction without changes being required.

40 The inclines *s* may be applied at both sides of springs *m* in case the car is to run in both directions, and the lever *o* may be compounded or fitted with gearing for obtaining more power to raise the rope.

Instead of the rope being clamped between a single moving clutch and a fixed bearing, there may be two swinging clutches operated by the hand-lever and fitted to receive the rope between their ends.

Having thus described my invention, I claim 50 as new and desire to secure by Letters Patent—

1. The clutching mechanism consisting of the slide *C*, sustained in guides *c*, fitted with springs, the clutch-lever *g*, lever *h*, and the 55 rod *i*, fitted to receive the endless cable and for being raised by movement of lever *h*, all combined with a car, for operation substantially as described and shown.

2. The combination, with the clutching devices fitted beneath the car for operation by a lever, of the rod *i*, fitted with springs *m*, for receiving the rope, and connected with a crank-arm that is operated by movement of the clutching-lever, substantially as shown and de- 60 scribed.

3. In combination with the lever for operating the clutch and the rod *i* that guides the rope, the shaft *n*, forked lever *o*, disk or arm *p*, and pin *p'*, substantially as shown, and for 70 the purposes set forth.

4. The rod *i* and springs *m*, for guiding the rope, provided with the pins *m'* and inclined flanges *s*, substantially as shown, and for the 75 purposes set forth.

5. In combination with the clutch *g*, lifting-rod *i*, and lever *h*, the swinging arm *q*, fitted to extend over the endless cable and connected by a link with the lever *h*, substantially as described and shown, and for the purposes 80 set forth.

SAMUEL M. PETTENGILL.
